UNITED STATES PATENT OFFICE.

ALFRED OLIVIER, OF NEUILLY-SUR-SEINE, FRANCE, ASSIGNOR TO SOCIÉTÉ
"PHILAURE," OF LEVALLOIS-PERRET, FRANCE.

APPARATUS FOR CLEANING CARD-CYLINDERS.

1,209,751.

Specification of Letters Patent. Patented Dec. 26, 1916.

Application filed April 15, 1915. Serial No. 21,570.

To all whom it may concern:

Be it known that I, ALFRED OLIVIER, citizen of the Republic of France, residing at 3 Rue Deves, Neuilly-sur-Seine, Seine, in the 5 Republic of France, have invented new and useful Improvements in Apparatus for Cleaning Card-Cylinders, of which the following is a specification.

This invention relates to an apparatus for 10 cleaning card cylinders by vacuum and essentially comprises as a main feature two horizontal cross bars or a bar and a threaded spindle that are parallel to the generating lines of the cylinders and serve either to 15 guide only or to guide and feed a carriage supporting a suction tube divided into two arms, which are adapted to the shape of the card and surround the latter to the required extent, so that the ends of these arms come 20 to lie in front of the cylinders at suitable points, *i. e.* as regards the doffing cylinder at a point beneath the cover plate and as regards the main cylinder in the space that is 25 uncovered by the door of the cover-plate when this door is opened.

The crossbars that support the carriage are fixed in two side plates each of which is provided with two cylindrical pins, the position of which can be adjusted, and that are 30 maintained by the supports used in sharpening the card. The side plate adjoining the pulley of the card carries the pivot of a lever which allows of opening from a distance the door of the cover-plate of the main cylinder, 35 this constitutes a very simple safety device which is moreover completed by a connection between said device and the clutch mechanism for feeding the card, for the purpose of preventing the restarting of the 40 feed motion after each stripping operation unless the door of the cover plate of the main cylinder has previously been closed.

An apparatus arranged according to this 45 invention has the advantage of being of a very simple and strong construction and that it can be placed in position without changing the parts of the card, while merely requiring a very simple and rapid initial adjustment. The carriage can be actuated 50 by anybody without any danger and while the cylinders are rotating at their normal speed, so that the stripping of the flocks of both cylinders can be made simultaneously and very rapidly. As the flocks are usually 55 unevenly distributed on the surface of the

cylinders, it is possible moreover in view of the fact that the apparatus is actuated by hand, to completely remove the flocks by retarding or accelerating the advancement of the carriage according to requirements. 60

In the accompanying drawing in which an apparatus arranged according to this invention is shown by way of example: Figure 1 is an elevational view and Fig. 2 a 65 plan view.

The apparatus comprises two side plates 1, 2 that are respectively mounted by means of adjustable cylindrical pins 5 on the two supports 3, 4 used for sharpening purposes that are arranged on the same side of the 70 card. The two side plates 1, 2 are braced by a crossbar 6 and a screw 7, that are parallel to the generating lines of the cylinders 8, 9 of the card. The whole rigid arrangement formed by the two side plates 1, 2, 75 crossbar 6 and screw 7 is fast on the card, pins 5 being adjusted so that screw 7 and crossbar 6 are horizontal, the whole contrivance being taken asunder for the purpose only of sharpening the mountings. 80

The crossbar 6 and screw 7 serve to guide the carriage 10 carrying the suction tube 14, during the displacement of the carriage along the cylinders that are to be stripped of their flock. The displacement is controlled by the screw 7 that advances a stud 11 fixed in the sleeve 12 of carriage 10. The screw 7 is actuated in one direction or the other by means of a removable crank 13. 85

The suction tube 14 mounted on the carriage 10 is divided into two arms 15, 16, that are firmly maintained by two supporting sleeves 17 of the carriage and are suitably bent and directed so that the end of arm 15 comes to lie in front of the doffing cylinder 8 beneath the cover plate, and that the end of arm 16 comes to lie in front of the main cylinder 9 in the space which is uncovered by the door of the cover plate when it is opened. Each of the arms 15, 16 has an aspirating nozzle 18 that can be adjusted at the required distance from the mountings in a simple and rapid manner by means of coupling sleeves 19. 95

On side plate 1, at the side of the card near the pulley, a lever 20 is pivoted that is provided with a stop pin 21 arranged to engage in the notches 22 of a segment 23 forming part of the side-plate 1. Lever 20 is connected by a connecting rod 24 with a 100 110

lug 25 fixed on the door 26 of the cover-plate 27 of the main cylinder, so as to be able to open this door at a distance when the cylinder is rotating at full speed.

- 5 In order to remove the flocks from the card, the workman intrusted with this work opens the door 26 by means of lever 20, so that he is obliged to keep at a distance from the main cylinder; by means of crank 13
 10 which he alone is able to control, he then turns the screw 7 in the right direction to shift the carriage 10 in front of the cylinders 8, 9. When the carriage has arrived at the end of its course, it is left there and
 15 brought back in the opposite direction during the following cleaning operation.

As is well known, the operator is obliged to stop the feed *i. e.* the supply of cotton to the main cylinder before he proceeds to the
 20 stripping operation and he of course restarts the feed as soon as the stripping is finished. The device for opening the door of the cover plate by means of the safety lever is connected to the clutch mechanism of the feed
 25 cylinder, so that the feed cannot be restarted until the door of the cover plate has been closed, any accident being thus rendered impossible. This mode of mechanical connection may of course be of any construction,
 30 and will depend on the clutch mechanism for the feed; no difficulty will be encountered by a man familiar with the art in establishing this connection in each case.

The invention is not restricted of course to
 35 details of execution shown and described, these details having been chosen only by way of example. The shifting of the carriage 10 in particular may without modifying the principle of this invention be effected by
 40 hand by means of a push button; screw 7 would then be suppressed and replaced by a second crossbar; lever 20 could moreover be removable, the workman who is intrusted with the stripping operation will have alone
 45 the control of this lever, and place the latter on the machine only during the cleaning operation.

Having now described my invention, what I claim as new and desire to secure by Letters Patent is:

1. In an apparatus for cleaning card cylinders, a suction nozzle, means for creating a suction through said nozzle, a carriage supporting the nozzle, two bars parallel to

the generating lines of the cylinder and upon 55 which the carriage is guided, one of said bars being screw threaded, means on the carriage for engaging with the screw thread, means for rotating the screw threaded bar, and a lever pivotally supported adjacent 60 said last named means remote from the main cylinder and through the intermediary of which lever the door in the cover plate of the main cylinder may be operated, substantially 65 as described and for the purpose set forth.

2. In an apparatus for cleaning card cylinders, a suction nozzle, means for creating a suction through said nozzle, a carriage supporting the nozzle, two bars parallel to 70 the generating lines of the card cylinder and upon which the carriage is guided, side plates carrying the bars at the ends, means for removably and adjustably securing said plates, upon the frame of the carding engine, and a lever pivoted to one of said side plates remote from the main cylinder through the intermediary of which lever the door in the cover plate of the main cylinder may be operated, substantially as described 75 80 and for the purpose set forth.

3. In an apparatus for cleaning card cylinders, a suction pipe divided into two branches, means for creating a suction through said pipe, a carriage supporting the 85 two branches so that one of the same lies in front of the doffing cylinder of the card, below the cover plate while the other lies in front of the main cylinder in the space which is uncovered by the door of the corresponding cover plate when it is opened, two bars parallel to the generating lines of the card cylinders and upon which the carriage is guided, side plates carrying the bars at the ends, a lever pivoted on one of said side 90 95 plates at a point remote from the main cylinder, and means for operatively connecting the lever to the door in the cover plate of the main cylinder, substantially as described and for the purpose set forth.

In testimony whereof I have signed my name to this specification in the presence of two subscribing witnesses.

ALFRED OLIVIER.
